UNITED STATES PATENT OFFICE

MICHAEL KIRNBAUER, OF FOREST PARK, ILLINOIS

AUTOMATIC DOOR RELEASE MECHANISM

Application filed December 7, 1932. Serial No. 646,123.

This invention relates to that type of automatic closing mechanisms for garage and like doors, in which the door is held in an open condition by a latching mechanism adapted to be operated to a release condition by a successive passage and operative engagement therewith of the front and rear wheels of a vehicle, to permit a closing mechanism associated with the door to become active and automatically effect a closure of the garage door, an example of which is disclosed in the subject matter of my prior Patent No. 1,620,109, dated March 8, 1927. And this improvement has for its objects:—

To provide a structural formation and combination of parts of an automatic closing mechanism for garage and like doors, and wherein a successive passage of the front and rear wheels of a vehicle can take place over the threshold of the garage doorway, before the closing mechanism of the door is fully released and permitted to effect an automatic closure of the door.

In the accompanying drawings:—

Fig. 1 is a longitudinal section elevation on line 1—1, Fig. 2 of a sliding garage door having the preferred form of the invention applied, with the door in an open position and latched therein.

Fig. 2 is a transverse section on line 2—2, Fig. 1, illustrating the twin door arrangement for garages intended for the reception of two motor vehicles.

Fig. 3 is an enlarged sectional elevation of the retarding means for checking the closing movement of the door in this improvement.

Fig. 4 is an enlarged side elevation with parts in section, of the latching mechanism in an open door latching condition.

Fig. 5 is a similar view of the latching mechanism, with the parts in condition for holding the door in an intermediate condition ready for a release movement, with a secondary upward movement of the latching bar of the mechanism.

Fig. 6 is a transverse section on line 6—6, Fig. 4, of the latching mechanism with parts in latching engagement with the door.

Like reference numerals indicate like parts in the several views.

In this improvement a garage door is shown supported on an overhead track 2, by the usual hangers 3, with a normal tendency to move to a closed condition under the influence of a flexible pull connection 4 and gravity weight 5, as illustrated in Fig. 1.

In the construction shown, the threshold or sill of the doorway is formed with a receiving channel for the reception of an open top casing 6 of approximately double the length of the door 1 and adapted to receive the lower edge of the same. Where the ordinary dual arrangement of garage doors is used, the same will have the usual parallel arrangement of overhead tracks 2 and open top casings 6, as illustrated in Fig. 2.

In the construction shown, a forward stop flange or lug 7 is fixed on the face of the door 1, adjacent to the lower advance corner of the door, and in connection with said forward stop lug 7, a rearward stop lug 8 is also fixedly attached to the door and arranged in a vertical plane below and to the rear of the main stop lug 7, the horizontal distance between the said stop lugs being less than the distance between the pair of ratchet teeth of the movable latching bar 9, now to be described.

The movable latching bar 9, of the latching means above referred to, is preferably of the bar type, pivotally mounted at its mid-length in the open top casing 6, with one arm carrying a gravity weight 10, and with the upper edge of its other arm projecting a distance above the threshold of the doorway for operative engagement by the wheels of a passing vehicle.

At the free end of the last mentioned arm of the latching bar 9, the same is formed with a pair of ratchet teeth 11 and 11' adapted for serial holding engagement with the aforesaid main stop lug 7 of the door, and said arm is also provided with a lateral lug 12 adapted for holding engagement with the aforesaid rearward stop lug 8 of the door 1.

The relative arrangement of the above described latching parts is such, that with a first depression of the latching bar 9 by the

passage over the same of the front wheel of a passing vehicle its ratchet tooth 11 will move down out of engagement with the forward stop lug 7 of the door and at the same time the lateral lug 12 of the ratchet bar 9 will move down into the path of the rearward stop lug 8 of the door, so that with a very slight movement of the door in a closing direction, said rearward stop lug 8 will move into holding contact with the stop lug 12 of the ratchet bar 9, and with the forward stop lug 7 of the door carried past its engagement with the aforesaid ratchet tooth 11. With the passage of the front wheel of the vehicle past the latching bar 9, the holding engagement between the aforesaid stop lug 12 and the rearward stop lug 8 is released, to permit the forward stop lug 7 to move into stop engagement with the ratchet tooth 11' of the latching bar 9, to still hold the garage door in an open condition. With a passage of a rear wheel of the vehicle over the latching bar 9, the same will be depressed to release the described holding engagement between the forward stop lug 7 and the ratchet tooth 11' with the garage door 1 free to move to a closed condition under the influence of the pull connection 4 and gravity weight 5 aforesaid.

30 Retarding means to prevent undue speed in the active operation of the above described ratchet release means so as to prevent a jump of the main stop lug 7 past the ratchet tooth 11' and a premature closing of the door 1, is provided and in the construction shown comprises:—

40 A depending track rail 13 having fixed association with the track rail 2, in adjacent relation to the left side of the doorway of the garage structure shown in Fig. 1, with the main under track face of said rail having a downward inclination away from such left hand end of the track, and at such left hand end is formed with abrupt upward extension 45 14, of such track face as shown in Fig. 3. And in parallel relation with said upward extension 14 of the track face, a supplementary inclined track rail 15 is fixedly secured in spaced relation to said track extension 14, to form a receiving and guiding passage for the track roller of the hydrostatic retarding means now to be described:

50 A closed fluid containing cylinder 16 is fixedly attached to the garage door 1, in aligned relation beneath the track extension 14 and supplementary rail 15. Said cylinder is of the closed type and provides a piston chamber for a piston head 17, the piston rod 18 of which passes through the up-

per head of the cylinder and carries at its upper end the track roller 19 for operative engagement with the track rail 13 and the passage between the track extension 14 and supplementary rail 15 above described.

70 A closed receiving chamber 20 is arranged in side relation to the cylinder 16 aforesaid, and has communication therewith by a larger connecting passage 21 at the mid-height of the interior of the cylinder 16, and by means of a smaller and controllable connecting passage 22 at the lower end of the interior of said cylinder 16.

75 The arrangement being such that until the piston head 17 passes and closes the larger passage 21, with such movement corresponding with the initial release movement of the present latching mechanism, little if any retarding action takes place. On the further downward movement of the piston head 17, further passage of the fluid from the cylinder 16 is directed wholly through the smaller and controllable passage 22 with a consequent retardance in the speed of action of the present latching mechanism, and with such retarding effect occurring at the same time that the ratchet tooth 11 is released from its stop engagement with the stop rib 7 of the door, a tendency to a sudden jump or skip of the stop rib 7 past one or both of the ratchet teeth 11, 11' of the ratchet bar 9, with a premature closing of the door is effectively prevented.

90 No claim is made in this application to the special construction of the above described retarding means.

95 Having thus fully described my invention what I claim as new, is:—

100 1. In a door release mechanism, the combination of a door, a forward stop lug and a rearward stop lug carried by the door with said lugs arranged in spaced horizontal and vertical relation one to the other, and a movable latching member adapted for serial operation by the front and the rear wheel 105 of a passing vehicle, said latching means being formed with a pair of holding notches adapted for serial engagement with the aforesaid forward stop lug and with a lateral stop lug adapted for stop engagement with the aforesaid rearward stop lug of the door, in attaining the serial release of the door in a closing movement of the same.

110 2. A door release mechanism as specified in claim 1 and wherein the latching member comprises a pivoted bar formed with a pair 115 of ratchet teeth at its free end.

MICHAEL KIRNBAUER.
